UNITED STATES PATENT OFFICE.

FERDINAND MORA CANDA, OF NEW YORK, N. Y.

CONTINUOUS PROCESS OF FORMING METAL BALLS.

Application filed May 21, 1924. Serial No. 714,969.

To all whom it may concern:

Be it known that FERDINAND MORA CANDA, a citizen of the United States, residing at New York city, in the county of New York and State of New York, has invented 5 certain new and useful Improvements in Continuous Processes of Forming Metal Balls, of which the following is a specification.

10 My invention relates to a method of forming balls from rod-stock by a series of successive steps and to an organization for carrying out the method in a manner to enable the whole process to be accomplished 15 at a single heat.

The object of my invention is to increase the output of ball rolling mills or plants and to reduce the cost of production.

For the purpose of disclosing my method 20 of operation and one organization of mechanism for performing the steps in sequence from the stock-bar to the finished balls, I shall refer to the accompanying drawings, in which—Figure 1 is a top plan view of 25 one arrangement of mechanism for carrying out my invention, the heating furnace being shown partly in section; Fig. 2, is a sectional view on the line 2—2 of Fig. 1; Fig. 3, is an end elevation, partly in section 30 on the line 3—3 of Fig. 1; Figs. 4, 5 and 6 are sectional views on the lines 4—4, 5—5 and 6—6 of Fig. 1, respectively; Fig. 7 is 35 a detail showing a bar being sheared by the cutter blades; and Fig. 8 is a sectional view on the line 8—8 of Fig. 7.

The long bars 10, as they are received from the rolling mill, are placed upon the inclined feed table 12 of the heating furnace 15, the table forming a continuation 40 of the floor or hearth of the heating chamber, which may be gas-fired or otherwise heated.

The hearth and feed table are provided 45 with a number of spaced ribs or supporting members 16, forming work supports which hold the rods above the furnace floor so that the flames and heat may completely envelop them. Certain of the ribs or supports are formed of pairs of specially shaped 50 fire brick 18, which are spaced apart to provide a channel or slot through which the reciprocable lifting members of the feed mechanism may operate. These lifting members preferably consist of carborundum 55 blocks or bricks 20 which are seated at

their lower ends in a groove in the upper side of the cast metal beam or carrier 21, the latter being water cooled by a longitudinal cavity 23, connected in any suitable manner with inlet and outlet water connections. Depending from the carrier beam 60 are integral lugs 25 which are pivotally connected to crank-arms 26, the latter being mounted on trunnions 27 supported by an I-beam 29 which supports the cast iron 65 bed plates 30. Reciprocating motion is imparted to the carrier beam of the feed device through connecting rods 32, pivoted at one end to pins 34 on the forward lug and at the other end to the crank-pin 35 of a 70 suitable motor 36.

As the feed device revolves, the rods 10 are intermittently lifted by the members 20 and carried forward a short distance, the rods being thus advanced through the furnace in a step by step manner. By the time 75 the rods drop into the channel 37 at the inner side of the floor or hearth, they are heated to the desired temperature. The rods are then grasped by tongs in succession and 80 inserted between the feed rolls 38 which carry the pairs of cutter blades 40, being driven by a suitable motor 41. As the long rods travel through the feed rolls, the cutter blades shear the rod into short lengths or 85 billets of uniform size, which are caught by the chains 43 of the endless conveyor and fed into the ball rolling machine 45, of the type shown in prior Patent No. 1,189,662, from whence they issue in the 90 form of balls.

The method above described is continuous process each step in the operation following in regular sequence and each part of the mechanism being coordinated to every other 95 part. The steps of heating, shearing and ball forming follow in quick succession so that there is little heat loss and the metal reaches the ball forming stage in proper condition to readily flow as it is displaced 100 by the ribs and shaped in the grooves of the ball rolling machine.

I claim:

1. The herein described method of forming balls from long stock-rods or bars, 105 which comprises feeding the rods progressively through a heating chamber, cutting the heated rods into billets of predetermined length, and while the metal is still hot rolling the billets between surfaces which 110

shape the metal into a plurality of spherical bodies.

2. An organized mechanism for forming balls from long stock-rods or bars in a continuous operation, comprising a heating chamber, means for progressively moving the rods through the chamber, a shearing device having means for withdrawing the rods from said chamber and shearing them into billets of predetermined length, ball rolling mechanism operating to sever the billets into blanks and shape the metal into spherical bodies, and conveying means operating to receive the billets from the shear-

ing device and to deliver them to the ball rolling mechanism.

3. An organized mechanism for forming balls from long stock-rods or bars in a continuous operation, comprising a heating chamber, shearing means, and ball forging mechanism, feeding means operating to transfer the rods from the heating chamber to the shearing means, and conveying means operating to transfer the severed billets from the shearing means to the ball forging mechanism.

In testimony whereof I affix my signature.
FERDINAND MORA CANDA.
